UNITED STATES PATENT OFFICE

AXEL LEVEDAHL, OF AURORA, ILLINOIS, ASSIGNOR TO AURORA AUTOMATIC MACHINERY COMPANY, OF AURORA, ILLINOIS, A CORPORATION OF ILLINOIS.

MEANS FOR ADVANCING OR RETARDING A MAGNETO-SHAFT RELATIVE TO A MOTOR-SHAFT.

1,027,056.

Specification of Letters Patent.

Patented May 21, 1912.

Application filed September 2, 1910. Serial No. 586,223.

To all whom it may concern:

Be it known that I, AXEL LEVEDAHL, a citizen of the United States, and a resident of Aurora, in the county of Kane and State 5 of Illinois, have invented certain new and useful Improvements in Means for Advancing or Retarding a Magneto-Shaft Relative to a Motor-Shaft; and I do hereby declare that the following is a full, clear, and 10 exact description thereof, reference being had to the accompanying drawings, and to the letters of reference marked thereon, which form a part of this specification.

This invention relates to improvements in 15 explosive engines and more particularly to certain novel features of construction for advancing or retarding the sparking period of the magneto without substantial change in the strength of the current which produces the spark.

The invention consists of the matters hereinafter described and more particularly pointed out in the appended claims.

In the drawings:—Figure 1 is a side elevation of an explosive engine, in this instance such as used more particularly with a motor cycle. Fig. 2 is a side elevation of the crank gearing casing and magneto with the cover of the gear casing removed. Fig. 3 is a view similar to that of Fig. 2 showing the parts in a different position. Fig. 4 is a partial section through Fig. 1 on the line 4—4 thereof, the section being shown on an enlarged scale. Fig. 5 is a partial section 35 through Fig. 1 on the line 5—5 thereof on an enlarged scale. Fig. 6 is a perspective view of a frame member to be more particularly described later.

10 indicates the cylinder of the engine; 11, 40 the crank case; 12, the crank-shaft; 13, the magneto; 13^a, the magneto shaft. The magneto shaft is driven in the usual manner by gearing interposed between the crank shaft and the magneto shaft. The magneto 45 is provided with any usual mechanism (not shown in the drawings) adapted to produce a spark at a certain predetermined point in the revolution of the magneto shaft, said point being preferably located so that a 50 maximum of current will be obtained from the magneto at the time when the spark is produced.

Magnetas, with which I am familiar, are usually provided with timing devices

which cause the spark to be produced either in advance of or back of a predetermined angular position of the magneto shaft at which the spark is normally produced, said position of the magneto shaft corresponding to that in which a maximum of current will be obtained. Thus, if the spark is either retarded or advanced, with reference to this position, it is produced by a current of less than the maximum. In carrying out my invention, instead of changing the time of the spark, with reference to the position of the magneto shaft, I change the angular position of the magneto shaft itself with reference to the crank shaft of the engine, maintaining the time of the spark, with reference to the position of the magneto shaft, in all cases the same. In this way the sparking position is always the position where a maximum of current is obtained, but by changing the relative angular relation of the magneto shaft to that of the crank shaft of the engine, the time when a certain diametric axis of the magneto shaft reaches the sparking position, 75 may be advanced or retarded.

The magneto shaft is provided with a gear 15 which is driven from a gear on the crank shaft by means of a gear 16 which I will call the driving gear, and an intermediate idle gear 17 which is mounted in the 80 gear casing 20. Said gears are inclosed in a gear casing 20. The gear 17 is journaled in a sliding frame 18, a perspective view of which is shown in Fig. 6. Said frame 18 is provided with apertures 18^a, 18^b in which is 85 mounted a stub shaft 19 on which the gear 17 is loosely journaled. The gear casing 20 has a rear wall 20^a and a front wall or cover 20^b. The frame 18 is slidably mounted in said casing so as to have a limited sliding 90 movement parallel to the plane of the gear 17 at right angles to a line connecting the central axes of the gears 15 and 16.

21 is a plate secured to the rear wall 20^a of the casing and provided with a groove 100 21^a in which the frame 18 slides. Said frame is held yieldingly in said groove by means of a flat spring 22 which is secured to the cover 20^b of the gear casing and bears at its ends on the top of said frame. The 105 frame 18 is provided with lugs 18^c, 18^d which are spaced apart and between which bears the rounded ends 25^a of a cross-bar 25

at the end of a rock arm 26. Said rock arm is made rigid with a short rock shaft 27 which has bearing in the front wall 20^b of the gear casing. The rock shaft projects through the cover of the casing and has rigidly connected to its outer end a lever 28 adapted to be actuated by an operating member 29 which is led into a suitable place for convenient manipulation in the usual manner. In the present instance said rocking lever 28 is shown as connected by a pin 30 and a slot 30^a to a link 31 which is operatively connected to a rocking lever 32 operated by the member 29. It is apparent that by means of the member 29, the rocking lever 28 may be moved to swing the rock arm 26. Said rock arm 26 will move the frame 18 to bring the axis of the gear 17 to one side or the other of the line connecting the central axes of the gears 15 and 16. Considering the gear 16 as relatively stationary, it will be apparent that this movement of the gear 17 with the frame 18, will cause a given diameter of the gear 15 to shift to the right or the left of its original position, thus advancing or retarding the magneto shaft with reference to the gear 16 and therefore with reference to the crank gear 12. In Fig. 3 I have shown the parts in position with the frame 18 and the gear 17 shifted to the right of the line connecting the central axes of the gears 15 and 16, in which case, considering the magneto shaft to be turning in the direction of the arrow, the sparking period will be lagged. A movement of said gear and frame in the opposite direction will advance the sparking period. It is to be noted that the relative shift of the one predetermined diametric axis of the magneto gear or driven gear relative to a certain diametric axis of the driving gear, will be effected whether the gears be at rest or in motion.

While I have illustrated and described herein a construction showing one embodiment of my invention, it is apparent that the details of construction may be modified without departing from the spirit of the invention, and I do not wish to be limited in any way thereby except as pointed out in the appended claims.

I claim as my invention:

1. In an explosive engine, in combination with a gear casing, a motor shaft mounted in said casing, a magneto, a driving gear actuated by the motor shaft, a driven gear having driving connection with the magneto, and an idle gear intermediate to, and intermeshing with, the said driving and driven gears, said idle gear being so movably mounted as to afford movement of its central axis in a direction transverse to a straight line passing through the axes of the said driving and driven gears, in a path separate from, and intermediate to, the two

circular paths in which said axis would travel if swung about the axes of said driving and driven gears, and means for shifting said idle gear relatively to the driving and driven gears.

2. In combination with a motor shaft, a magneto and magneto shaft, a driving gear actuated by the motor shaft, a gear on the magneto shaft, an idle gear intermediate to, and intermeshing with, said driving gear and said magneto gear, a sliding frame in which said idle gear is journaled, said frame being adapted to move in a direction transverse to a straight line connecting the central axes of the driving and magneto gears, and means for shifting said frame to move the central axis of said idle gear to one side or the other of said straight line.

3. In an explosive engine, in combination with a gear casing, a motor shaft mounted in said casing, a magneto and a magneto shaft, a driving gear actuated by the motor shaft, a gear on the magneto shaft, an idle gear intermediate to, and intermeshing with, said driving gear and said magneto gear, a sliding frame in which said idle gear is journaled, said frame being mounted in said casing and adapted for movement in a direction transverse to a straight line connecting the central axes of said driving and magneto gears, a rock shaft journaled in said casing, a rock arm on said shaft, means connecting said rock arm with said sliding frame and means for actuating said rock shaft to shift said frame for moving the central axis of the idle gear to one side or the other of said line.

4. In an explosive engine, in combination with a gear casing, a motor shaft mounted in said casing, a magneto and a magneto shaft, a driving gear actuated by the motor shaft, a gear on the magneto shaft, an idle gear intermediate to, and intermeshing with, said driving gear and said magneto gear, a sliding frame in which said idle gear is journaled, said sliding frame being mounted in said casing and adapted for movement in a direction transverse to a straight line connecting the central axes of said driving and driven gears, said frame being provided with laterally extending lugs, a rock shaft journaled in said casing, a rock arm on said shaft adapted to engage said lugs, and means for actuating said rock shaft to shift said frame for moving the central axis of the idle gear to one side or the other of said straight line.

5. In an explosive engine, in combination with a gear casing having front and rear walls, a motor shaft mounted in said casing, a magneto and a magneto shaft, a driving gear actuated by the motor shaft, a gear on the magneto shaft, an idle gear intermediate to, and intermeshing with, said driving gear and said magneto gear, a sliding frame in

which said idle gear is journaled, said frame being mounted in a guide recess in the rear wall of said casing and adapted for movement in a direction transverse to a straight line connecting the central axes of said driving and driven gears, lugs on said sliding frame, a rock shaft journaled in said casing, a rock arm secured to said rock shaft and adapted to engage said lugs, and means for actuating said rock shaft to shift said frame for moving the central axis of the idle gear to one side or the other of said line.

6. In combination a driving gear, a driven gear, an idle gear intermediate to, and intermeshing with, the said driving and driven gears, said idle gear being so movably mounted as to afford movement of its central axis in a direction transverse to a straight line passing through the axes of the said driving and driven gears, in a path separate from, and intermediate to, the two circular paths in which said axis would

travel if swung about the axes of said driving and driven gears, and means for shifting said idle gear relatively to the driving and driven gears.

7. In combination, a driving gear, a driven gear, an idle gear intermediate to, and intermeshing with, said driving gear and driven gear, a sliding frame in which the said idle gear is journaled, said frame being adapted to move in a direction transverse to a straight line connecting the central axes of the driving and driven gears, and means for shifting said frame to move the central axis of said idle gear.

In testimony, that I, claim the foregoing as my invention I affix my signature in the presence of two witnesses, this 23rd day of August A. D. 1910.

AXEL LEVEDAHL.
